UNITED STATES PATENT OFFICE.

CHARLES H. KORS, OF POUGHKEEPSIE, NEW YORK.

COVERED RECEPTACLE.

1,232,936.

Specification of Letters Patent. Patented July 10, 1917.

Application filed October 20, 1916. Serial No. 126,652.

To all whom it may concern:

Be it known that I, CHARLES H. KORS, a citizen of the United States, residing at Poughkeepsie, county of Dutchess, State of New York, have invented a certain new and useful Improvement in Covered Receptacles, of which the following is a full, clear, and exact description.

My invention relates to covered receptacles and has for its object to produce a normally closed receptacle having a simultaneously acting closure which can be easily opened by a substantially direct movement of the hand in reaching toward and into the same, the purpose being to produce a receptacle with a cover which is substantially non-interfering since it can be opened and the contents inserted or removed by a direct and almost involuntary one hand operation substantially the same as though the receptacle were not covered and automatically closes as the hand is removed, so that its opening action and closing action are simultaneous with the mere insertion and removal of the hand.

The following is a description of an embodiment of my invention, reference being had to the accompanying drawings, in which—

30 Figure 1 shows in perspective an open receptacle embodying my invention, the same being secured to the edge of a table;

Fig. 2 is a view of the left hand end of the receptacle;

35 Fig. 3 is a section of the same on the line 3—3 Fig. 4;

Fig. 4 is a front elevation with portions of the right hand end broken away;

40 Fig. 5 is a plan view of a modified form of my invention, and

Fig. 6 is a side view of the same partly in section.

Referring more particularly to the drawings, 1 is a container-body having a cover 2 hinged thereto so as to open when its forward edge is raised. In order that the cover may be raised by a direct movement of the hand as it enters the receptacle without requiring a voluntary opening movement in

50 addition to the reaching movement, I have added to the cover an extension 3 which projects forward beyond the container-body and constitutes a hand rest in that it is adapted to rest on the back of a hand entering the box. The hand rest 3 projects so as to extend over a considerable portion of the

hand, say, one-half its width or more, and is preferably provided with a gradually rising under-surface 4, which lies in the path of the hand of the user as it is in the act 60 of moving horizontally toward the container, so as to enter the same. The under-surface of the hand rest guides the hand and results in the opening and closing actions of the cover. The extension 3 is adjacent to 65 one end of the cover.

The box shown in Figs. 1 to 4 is intended for use as a cigar worker's box for holding wrappers and as such is secured to the left hand end of a table 7 by suitable 70 brackets 8, so that the hand rest 3 is slightly above the top of the table. In using this box the operator sits at the front of the table with the box to his left so that it can be reached by a slight forward reaching 75 with his left hand, and when he desires to insert or remove something from the box by his left hand extends that hand toward the mouth of the box with substantially the same movement that would be made if no 80 cover were present or with a slightly and almost if not quite involuntary rise as the under-surface of the extension 3 is engaged by the back of the hand. As the hand in this movement engages the under side of 85 the extension it causes the cover to rise out of the way of the hand so that the hand can easily enter the receptacle. Upon the withdrawal of the hand the cover falls to closed position. In order to provide means for 90 raising the cover to a more nearly vertical position than would otherwise be attained with a given movement of the hand alone, I provide the end of the cover adjacent to the extension with a downward projection 95 9, which projection has a downwardly facing curved surface 10 which as the hand moves over the end of the box engages the back of the hand or wrist so that the upward movement of the cover continues.

100 By the means described a box is provided which can easily be opened by a single movement of the hand which is substantially the same as would be necessary to reach into the box were no cover present.

105 In the modification shown in Figs. 5 and 6 my invention is embodied in a device which may be used to contain a cigar maker's paste holder. It consists of a receptacle 11 preferably secured to the table by a screw 110 and being provided at its upper end with a band 12 to which is hinged at 13 a cover

14. This cover is provided with an extension 15 projecting beyond the receptacle and having an upwardly extending lower surface 16 on its projection portion. It also has a stop 17 which acts to prevent the cover from being raised beyond its dead center. In a device of this character the upwardly extending surface 16 preferably extends about two-thirds around the periphery of 10 the cover so that engagement can be made by a hand or finger moving toward the center of the receptacle from either the front of the receptacle or the sides thereof. When this device is used to hold a paste 15 cup such as 18 into which a cigarmaker ordinarily dips with one finger, the finger is moved toward the paste cup container with a substantially horizontal movement until it engages some portion of the curved surface 16. This engagement causes the cover 14 to lift with the result that the finger can be moved downward into the paste cup, the movements being substantially the same as would be necessary to dip into the paste cup 20 25 if no cover were present. When the finger is removed the cover automatically closes.

The features above described result in producing a closed receptacle which keeps the contents moist if desired and protects 30 them from dust and dirt and preserves them in a sanitary condition and yet does not interfere substantially with the speed of an operator or the movements which would be necessary if the receptacle were not closed.

35 In a cigar worker's box of Figs. 1 to 4 inclusive in order to make the cover open more easily I prefer to hinge the cover to a folding strip 20 which is hinged at 21 to the rear portion of the receptacle body so as 40 to fold downward. The cover 2 is hinged to the folding strip on the line 22 and the cover itself is guided by links 23 pivotally connected to its sides at intermediate points 24 and to the receptacle body at points 25. 45 Mounting the cover in this way makes it open more easily than a cover hinged in the ordinary manner but this mounting is not essential to an embodiment of my invention. The links 23 are housed in the end walls of 50 the receptacle, as shown in Fig. 4, and a filler 26 is provided preventing the contents of the box from getting behind the folding strip 20.

The cover, as it rises, engages the edge of 55 the flange 27, so as to be stopped thereby before it passes its dead center, with the result that it closes automatically whenever it is released and cannot be accidentally left open. The cover is provided with a depending 60 flange 28 and can carry a moistener 29 shown in Fig. 3, so that the moistener is not liable to be touched by the operator's hand. The upper edge of the container is cut away behind the curved portion 4 and the projection 65 9, as shown at 30 in Figs. 1, 2, 3 and 4, to

facilitate the entry of the hand into the container, that being helpful where the surface 4 extends below portions of the container top. The cutting away of the upper corner is particularly useful in a cigar 70 worker's box.

The cigar worker's box embodying my invention is actually a time and labor saving device, since the cloth heretofore used to cover wrappers required two hands and several movements for the removal and replacement of the cloth and the extraction of a wrapper, thus calling for more time and labor than is called for by the simple and direct reaching action necessary when my 80 invention is used. It also saves material as it keeps the wrappers in better and more uniform condition than they can be kept in by a damp cloth.

As will be evident to those skilled in the 85 art, my invention permits of various modifications without departing from the spirit thereof or the scope of the appended claims.

What I claim is:

1. A closed receptacle having a body portion and a cover hinged thereto, provided with an extension adapted to be engaged by the back of the hand when said cover is in closed position, and so shaped that a continued movement of the hand in a substantially horizontal plane will move the cover to open position. 90 95

2. In a closed receptacle, the combination of a container, a cover hinged thereto and normally tending to move to closed position, 100 and an extension on said cover projecting laterally beyond said container and adapted to be engaged by the back of the hand of the user, when said cover is closed, so as to lift said cover and so shaped that a continued movement of the hand in a substantially horizontal plane will move the cover to open position. 105

3. In a closed receptacle, the combination of a container, a cover hinged thereto and normally tending to move to closed position, 110 and an extension on said cover projecting beyond said container and when the cover is closed having an under surface gradually receding upward from the container and adapted to be engaged by the back of the hand of the user. 115

4. In a closed receptacle, the combination of a container, a cover hinged thereto and normally tending to move to closed position, 120 said cover being provided at its front side with an extension having when the cover is closed an under surface adapted to be engaged by the back of the hand of the user, said cover having at one end a depending 125 flange having a curved lower surface.

5. In a closed receptacle, the combination of a container, a cover hinged thereto and normally tending to move to closed position and an extension on said cover project- 130

ing beyond said container and having an under surface gradually receding from the container when the cover is closed, said container having a cutaway portion adjacent to said extension when the cover is closed.

6. In a closed receptacle, the combination of a container, a cover hinged thereto and normally tending to move to closed position, and an extension on said cover projecting laterally beyond said container and adapted to be engaged by the back of the hand of the user, when said cover is closed, so as to lift said cover, a strip hinged to said container and to which said cover is hinged, and links connected to the ends of the cover at intermediate points and to said container.

7. In a closed receptacle the combination of a container, a cover hinged thereto and normally tending to move to closed position and an extension on said cover projecting beyond said container when the cover is closed, said projection having an under sur-

face adapted to be engaged by the back of the hand of the user and extending to a point adjacent to one end of the cover, and being so shaped on its engaging surface that a continuous movement of the hand in a substantially horizontal plane will move the cover to open position.

8. In a closed receptacle the combination of a container, a cover hinged thereto and normally tending to move to closed position and an extension on said cover projecting beyond said container when the cover is closed, said projection having an under surface adapted to be engaged by the back of the hand of the user, said extension beginning substantially midway of the cover and extending to a point adjacent to one end of the cover and being so shaped on its engaging surface that a continued movement of the hand in a substantially horizontal plane will move the cover to open position.

CHARLES H. KORS.
